METHOD OF MAKING A BRAKE SHOE

Rudolph A. Goepfrich, South Bend, Ind., assignor to Bendix Aviation Corporation, South Bend, Ind., a corporation of Delaware

Original application March 15, 1928, Serial No. 261,714. Divided and this application June 15, 1932. Serial No. 617,459

6 Claims. (Cl. 29—152.1)

This invention relates to the method of making brake shoes, and is illustrated as embodied in the manufacture of a rigid curved shoe for an internal expanding automobile brake. An object of the 5 invention is to provide greater rigidity for a shoe of this character, by forming or displacing portions of the stiffening web crosswise of the shoe, preferably in such a manner that the web undulates crosswise of the shoe. The shoe may be 10 formed of an element having a straight web which is integral with the rim, and preferably also integral with an inner reinforcing flange, at intervals which alternate with portions that are structurally separate from the rim and flange and 15 which are displaced crosswise of the shoe and then, if desired, welded or otherwise secured again to the rim and flange.

Other objects and features of the invention, including novel constructions at the ends of the 20 shoe and various desirable details of construction, will be apparent from the following description of two illustrative embodiments shown in the accompanying drawing, in which:

Figure 1 is a curved section, lengthwise of the 25 shoe, on the line 1—1 of Figure 2, showing the undulation of the web;

Figure 2 is a section through the shoe on the line 2—2 of Figure 1;

Figures 3 and 4 are views corresponding respectively to Figures 1 and 2, but showing a different shoe;

Figure 5 is a side elevation of the shoe of Figures 3 and 4; and

Figure 6 is a view of the inner side of the shoe 35 of Figures 3 and 4.

The illustrated shoes are formed of elements, either formed in the curved shape shown or bent from straight members, and each having an outer rim 10 (to which the brake lining 12 is riveted 40 or otherwise secured) and preferably also an inner reinforcing flange 14. The rim and flange are connected by a web 16 (Figs. 1 and 2) or 18 (Figs. 3—6) having at intervals portions which are integral with the rim and flange, these portions of web 16 being along one side of the shoe, while the corresponding portions of web 18 are 45 between the side edges of the shoe substantially in the central plane of the shoe.

Between the integrally-connected portions of 50 the webs 16 and 18 are structurally-separate portions 20 and 22, preferably formed by cutting or otherwise severing the web at top and bottom, these portions being displaced crosswise of the shoe and if desired again secured to the rim and flange by welds 24. The portions 22 of web 18 are

shown alternately displaced in opposite directions. In either case, the result is a web undulating crosswise of the shoe.

At the anchored end of the shoe, portions 26 and 28 of the rim and flange are bent smoothly 60 around and welded to the end of the web, which is here formed with an opening for an anchor pivot 30. As best appears in Figure 6, the web 18 is preferably at one side of the shoe at its anchored end, so that it will come next the backing 65 plate of the brake and permit the use of a very short and rigid anchor pin.

At the other end of the shoe the web 18 is 70 preferably in the central plane of the shoe, and portions 32 and 34 may be folded across and welded to this end of the web to form a support for a hardened cam or wear plate 36 secured thereto.

While two illustrative embodiments have been described in detail, it is not my intention to limit 75 the scope of the invention to the method of making those particular embodiments, or otherwise than by the terms of the appended claims.

This application is a division of my copending application, Serial No. 261,714, filed March 15, 80 1928, entitled "Brake shoes".

I claim:

1. That method of making a brake shoe which comprises forming an element with a rim and a stiffening web integral with the rim at intervals 85 alternating with intervals in which its entire width is structurally separate from the rim, and then displacing the structurally separate parts of the web crosswise of the rim to give support to said rim over a broad area.

2. That method of making a brake shoe which comprises forming an element with a rim and a spaced reinforcing flange and with a stiffening web integral with the rim and flange at intervals 95 alternating with intervals in which its entire width is structurally separate from the rim and flange, and then displacing the structurally separate parts of the web crosswise of the rim and flange to give support to said rim and flange over their entire width.

3. That method of making a brake shoe which comprises forming an element with a rim and a stiffening web integral with the rim at intervals 105 alternating with intervals in which it is structurally separate from the rim, and then displacing the structurally separate parts of the web crosswise of the rim, and finally welding the displaced parts of the web to the rim.

4. That method of making a brake shoe which comprises forming an element with a rim and a 110

- spaced reinforcing flange and with a stiffening web integral with the rim and flange at intervals alternating with intervals in which it is structurally separate from the rim and flange, and
- 5 then displacing the structurally separate parts of the web crosswise of the rim and flange, and finally welding the displaced parts of the web to the rim and flange.
- 10 The method of making a brake shoe from a structural shape having a web, which comprises severing sections of the web along its edge at intervals from the remainder of the structural shape

and stretching and displacing the web laterally at its severed sections to increase the breadth of support for the remainder of the structural shape.

6. The method of making a brake shoe from a structural shape having a web, which comprises 80 severing sections of the web along its edge at intervals from the remainder of the structural shape, stretching and displacing the web laterally at its severed sections and securing said displaced web sections to the remainder of the structural 85 shape.
